Inventor,

Karl Kreutzer

By Young, Emery & Thompson Atty's.

UNITED STATES PATENT OFFICE

114,955

DESIGN FOR A PENCIL

Karl Kreutzer, Nuremberg, Germany, assignor to Firma J. S. Staedtler, Nuremberg, Germany

Application November 21, 1938, Serial No. 81,276

Term of patent 14 years

To all whom it may concern:

Be it known that Karl Kreutzer, a citizen of Germany, residing at Nuremberg, Germany, has invented a new, original, and ornamental Design for Pencils, of which the following is a specification, reference being had to the accompanying drawing, forming part thereof.

Fig. 1 is a perspective view of a pencil showing my new design; and

Fig. 2 is an end view of Fig. 1.

I claim:

The ornamental design for a pencil, as shown.

KARL KREUTZER.
